UNITED STATES PATENT OFFICE.

THOMAS H. COULTER, OF LYITLE, TEXAS.

METHOD OF STRETCHING AND SECURING WIRE.

1,338,425.

Specification of Letters Patent. Patented Apr. 27, 1920.

Application filed June 25, 1918, Serial No. 241,844. Renewed March 5, 1920. Serial No. 363,595.

To all whom it may concern:

Be it known that I, THOMAS H. COULTER, a citizen of the United States, residing at Lytle, in the county of Atascosa and State 5 of Texas, have invented a new and useful Method of Stretching and Securing Wire, of which the following is a specification.

It is the object of this invention to provide a novel method for taking up the slack 10 in a flexible member of any kind, such as fence wire.

With the above and other objects in view, the invention consists in the process, and in the steps thereof, hereinafter described and 15 claimed, it being understood that, within the scope of what is claimed, changes falling within the skill of a mechanic may be made without departing from the spirit of the invention.

20 In the accompanying drawings:—

Figure 1 shows in elevation, a flexible element which has become slack, it being presupposed that the process hereinafter described is to be put into operation for the 25 purpose of tightening the flexible element;

Fig. 2 is a plan view illustrating one step in the process;

Fig. 3 is a plan view illustrating a tie which is used in the process;

30 Figs. 4, 5, 6 and 7 are detail views illustrating the various successive steps in the process; and

Fig. 8 is a plan view disclosing the twisting device.

35 In Fig. 1, the numeral 1 indicates a flexible element of any kind, such as a fence wire, which has become slack, and this invention proposes a method for tightening such a slack wire.

40 The wire 1 is cut apart to form ends 2 and 3. A loop 4 is made in the end 2, and a loop 5 is made in the end 3.

In Fig. 3 there is shown a U-shaped tie 6 comprising a bend 7 and arms 8 and 9. 45 The invention contemplates the use of a twisting device or crank 11, shown in Fig. 8, and having a hole 12.

The bend 7 of the tie is twisted as shown at 10 in Fig. 4 around the loop 4, and the 50 arms 8 and 9 are extended upwardly through the loop 5.

The twisting device 11 is placed on top of the loop 5 as seen in Fig. 5, the arm 8 of the tie being extended through the hole 12.

55 The twisting device 11 is rotated, the arm

8 being wound on the twisting device as shown at 14, and the arm 9 extending backwardly as shown in Fig. 5. In this way, the ends 2 and 3 of the wire are drawn together.

The arm 9 is then bent back across the end of the loop 5 as shown at 15 in Fig. 6 and is twisted, in spaced convolutions 16, around the body of the tie 6. This step holds the ends 2 and 3 of the wire against 60 separation. The twist 14 in the arm 8 is then unwrapped from the tightening device 11 and is bent back across the end of of the loop 5, and is wrapped around the body of the tie 6, in convolutions 17, which, 65 as shown in Fig. 7, lie between the convolutions 16 of the arm 9.

From the foregoing it will be seen that a simple but expeditious process is provided, whereby the slack may be taken out of a 70 wire, and whereby the severed portions of the wire may be reunited.

Having thus described the invention, what is claimed is:—

1. A method of tightening and connecting two flexible members, which consists in fashioning a first loop in one member; fashioning a second loop in the other member; connecting the bend of a U-shaped tie with the first loop; passing the arms of the tie 85 through the second loop; twisting one arm of the tie around a tightening device at the second loop to draw the flexible elements together; bending the other arm of the tie backwardly across the second loop and connecting said other arm with the body of the tie between the loops; untwisting the first specified arm from the tightening device; bending the first specified arm backwardly 90 across the second loop; and connecting the first specified arm with the body of the tie between the loops.

2. A method of tightening and connecting two flexible members, which consists in fashioning a first loop in one member; fashioning a second loop in the other member; connecting the bend of a U-shaped tie with the first loop; passing the arms of the tie through the second loop; twisting one arm of the tie around a tightening device at the 100 second loop to draw the flexible elements together; bending the other arm across the second loop and winding said other arm around the body of the tie, between the loops, in a plurality of spaced convolutions; 105

untwisting the first specified arm from the tightening device; bending the first specified arm backwardly across the second loop; and twisting the first specified arm around the body of the tie between the loops, in convolutions which are located between the convolutions of said other arm.

In testimony that I claim the foregoing as my own, I have hereto affixed my signature in the presence of two witnesses.

T. H. COULTER.
